UNITED STATES PATENT OFFICE

DRAIN VALVE FOR SINKS AND THE LIKE

Frank Muckler, Sappington, Mo., assignor to
Southern Equipment Company, St. Louis, Mo.,
a corporation of Missouri

Application May 26, 1949, Serial No. 95,502

4 Claims. (Cl. 4—198)

1
This invention relates to sinks, tubs and the like of the type having a drain pipe equipped with a stop valve and an overflow communicating with said drain pipe.

Heretofore the overflow pipe has been independently connected to the drain pipe below the drain valve therein, which necessitated additional fittings and adequate space. The principal object of the present invention is to eliminate these requirements by means of a novel arrangement wherein the overflow pipe is connected with the drain valve and an open overflow is provided through said valve in both open and closed positions thereof. Other objects are to provide for stopping the rotary plug of the drain valve in a positively closed, as well as a full drain, position and to provide a combination drain and overflow valve of simple, economical and compact construction.

In the accompanying drawings, which form part of this invention and wherein like symbols refer to like parts wherever they occur.

Fig. 1 is a side elevational view of a sink provided with a combination overflow and drain valve embodying my invention.

Fig. 2 is an enlarged vertical fragmentary sectional view on the line 2—2 in Fig. 1, showing the valve opened.

Fig. 3 is a view similar to Fig. 2, showing the valve closed.

Fig. 4 is a vertical sectional view on the line 4—4 in Fig. 3.

Fig. 5 is a front elevational view of the closed valve.

Fig. 6 is a side elevational view of the rotary valve plug; and

Fig. 7 is an end elevational view of the open end of said valve plug.

In the accompanying drawings, my invention is illustrated in connection with a sink 1 having a pipe 2 leading downwardly outside thereof from an overflow opening 3 in the upper position of one side thereof. The bottom of the sink 1 has a drain opening therein defined by an annular flange 4 which slopes downwardly towards said opening. The sink is provided with a drain or waste pipe 5 communicating with said drain opening through a combination drain and overflow valve comprising a casing 6 having a passageway 7 that extends vertically therethrough and has an enlarged counterbored, internally threaded upper end portion 8 and a lower end portion 9 which is internally threaded to receive the drain pipe 5 and is externally threaded to receive a larger drain pipe (not shown).

2
The upper end 8 of the valve casing 6 is beveled in conformity with the conical flange 4 that defines the drain opening in the bottom of the sink 1 and said end is clamped to the underside of said flange by a ring 10 which is threaded into the enlarged upper end 8 of the passageway 7 and which has an outstanding rim flange 11 whose underside is beveled in conformity with said sink flange 4 and seats on the upper surface thereof. A washer 12 is interposed between the sink flange 4 and the beveled upper end of the valve casing 6 to prevent leakage. A flat strainer disk 13 seats in the ring 10 flush with the top thereof and is secured thereto by screws 14.

The valve casing 6 has a cross-bore 15 which extends therethrough intermediate between the upper and lower ends thereof and is enlarged where it intersects the vertical passageway 7 to form cylindrical valve seat 16. Extending into the cross-bore 15 of the casing 6 from one side thereof is a valve stem 17 which terminates at its inner end in a cylindrical valve member 18 that is journaled for rotation in the cylindrical valve seat 16. The lower end of the overflow pipe 2 is connected to the cross-bore 15 on the other side of the valve casing 6. The rotary cylindrical valve member 18 is provided with a diametral passageway 19, which extends therethrough from side to side of the vertical passageway 7 in the valve casing, a radial port 20 leading from said diametral passageway and opening through one side of said valve member, and an end port 21 in continuous communication with said diametral passageway and the end of the cross-bore 15 which communicates with the lower end of the overflow pipe 2. In the open position of the rotary valve member 18, the diametral passageway 19 thereof is in line with the vertical passageway 7 in the valve casing 6 and thus permits water to drain from the sink 1 into the drain pipe 5 and the overflow water to drain through the axial end port 21 and diametral passageway into the vertical passageway and thence into the drain pipe. In the closed position of the valve member 18, the diametral passageway 19 is disposed crosswise of the vertical passageway 7 thereby cutting off communication between the sink and drain pipe 5, but the side port 20 opens downwardly into the drain pipe and thus permits the overflow water to flow through the end port 21, thence into said diametral passageway and thence through said side port into said drain pipe.

As shown in Fig. 4, the cylindrical valve member 18 is held in the valve seat 16 by means of a retainer nut 22, with its packing 23 and the seal-

ing nut 24. For remote rotary manipulation, the valve stem 17 may be connected with an actuating rod 25 having a socket portion 26 adapted to receive the outer end of the valve stem which is rigidly held thereon by a set screw 27. Another screw 28 is threaded through the socket portion 26 into the valve stem 17 and is of sufficient length so that when said valve stem is turned to either valve opening or closing position the stop screw 28 will contact a stop pin 29 or a stop pin 30 fixed to the valve casing 6 one on each side of the valve stem and limit the turning of the rotary valve member to a drain shut off position or to a full drain position, and also assure full communication between the overflow pipe 2 and the drain pipe 5 in both of these positions.

It is apparent from the foregoing that the overflow pipe 2 is always in direct communication with the drain pipe 5 leading to the sewer. When the rotary member 18 is positioned to shut off drainage from the sink, the overflow can pass from the cross passage 19 through said valve member and through the side port 20 into the drain pipe 5. When the drain valve is open, the overflow may pass directly through the cross passage 19 into the drain pipe 5. This safety feature of the overflow is never disturbed. The open and closed positions of the valve are positively determined by the stop pins 29 and 30. The direct connection of the overflow pipe 2 with the valve and the possibility of direct connection of the outlet of the drain valve to the drain pipe makes it possible to use a minimum number of parts and a minimum amount of materials and cost. The valve is firmly clamped to the bottom of the sink by the ring nut 10, and this nut provides a depressed seat for the flat strainer disk 31 secured thereto.

What I claim is:

1. In a sink having an overflow pipe, a drain opening, and a drain pipe communicating with said drain opening, the improvement which consists in providing said drain pipe with a valve clamped to the bottom of said sink around the drain opening therein by means of a ring that extends through said drain opening and has a circumferential flange supported by the bottom of said sink around the drain opening therein, said valve secured to said ring, said valve having a rotary cylindrical valve member for establishing and cutting off drainage from said sink through said drain pipe and for maintaining communication between said overflow and drain pipes through said valve in all positions of said rotary valve member.

2. In a sink having an overflow pipe, a drain opening, and a drain pipe communicating with said drain opening, the improvement which consists in providing said drain pipe with a valve

clamped to the bottom of said sink around the drain opening therein by means of a ring that extends through said drain opening and has a circumferential flange seating on said bottom of said sink around the drain opening therein, said valve being threaded into said ring, said valve having a rotary cylindrical valve member for establishing and cutting off drainage from said sink through said drain pipe and for maintaining communication between said overflow and drain pipes through said valve in all positions of said rotary valve member and a strainer disk secured to said ring substantially flush with the top thereof.

3. In a sink having overflow pipe, a drain pipe and a stop valve for said drain pipe, the improvement which consists in providing said valve with a rotary cylindrical valve member for establishing and cutting off drainage from said sink through said drain pipe and for maintaining communication between said overflow and drain pipes through said valve in all positions of said rotary cylindrical valve member, said rotary cylindrical valve member provided with a passageway extending through said rotary valve member from side to side thereof for establishing communication between said sink and said drain pipe in one position of said valve member, a port extending through one end of said valve member for establishing communication between said overflow pipe and said passageway in all positions of said valve member, and a second port extending through one side of said valve member for establishing communication between said passageway and said drain pipe when said valve member is rotated to a position to cut-off drainage from said sink through said passageway.

4. The combination set forth in claim 3 wherein in said rotary valve member is provided with an exposed valve stem having a pin extending radially therefrom and said valve is provided with a pair of fixed stop pins adapted to be engaged by said radial pin for limiting the rotary movement of said valve member.

FRANK MUCKLER.
